PAPER BAG

Filed May 21, 1930

D. O. Inventor
Isabelle B. Blake.

Inventor:

884 Frederick W. Barker,
Attorney.

UNITED STATES PATENT OFFICE

ISABELLE B. BLAKE, OF NEW YORK, N. Y.

PAPER BAG

Application filed May 21, 1930. Serial No. 454,893.

This invention relates to receptacles and the improvements are directed to a novel form of paper bag formed from a single piece of material.

5 Primarily, the object of the present invention resides in the provision of a blank for forming a bag of the above-mentioned character, said blank being provided with indications, in the form of lines, or the like, whereby 10 said blank may be folded to produce a bag having an oblong bottom devoid of seams.

A subsidiary object is the arrangement of 15 additional lines whereby the formed bag may be collapsed or folded to assume a compact form to facilitate the shipment or handling thereof.

An additional object of the invention is the provision of a blank which is susceptible of variance in order that formed bags having 20 desired dimensions may be produced.

With these objects in view, together with others which will appear as the description proceeds, the invention resides in the novel formation, combination and arrangement of 25 parts, all as will be described more fully hereinafter, illustrated in the drawings, and particularly pointed out in the claims.

In said drawings:

Figure 1 is a view of the blank from which 30 the bag is formed, the dot and dash lines indicating the lines on which the material is folded.

Fig. 2 is a fragmentary view illustrating one step in the folding of the blank.

35 Fig. 3 is a similar view showing one end of the bag completed.

Fig. 4 is a perspective view of the completed bag.

Fig. 5 is a view showing the bag partially 40 collapsed; and

Fig. 6 is a view showing the receptacle completely collapsed.

Referring now more in detail to the accompanying drawings, wherein like characters 45 of reference indicate similar parts throughout the several views, let A denote the blank, and upon inspection of Fig. 1 it will be observed that said blank is provided with a series of lines which indicate the lines on 50 which said blank is folded. Said lines have

been designated by certain numerals arranged sequentially in the order of folding, as will presently appear, but at this time it is pointed out that the bottom of the completed bag is bounded by lines 12, 14, 18 and 21, whereby the desired oblong structure is produced. Lines 21 and 13, arranged at right angles to said line 12, and lines 17 and 24, at right angles to said line 18, respectively form the opposite sides of the receptacle, while lines 10, 15 and 19 and 22 cooperate with their respectively arranged fold lines to produce the ends of the bag. The other fold lines will be referred to during the disclosure of the method of folding the blank 60 to produce the structure shown in Fig. 4.

As a first step said blank is folded upwardly on the lines 10 and 10a, the lines 11, 12 and 13 being also folded upwardly until the line 10 coincides with line 14, as indicated in Fig. 2. Certain parts are now in an erect position, as shown in said figure. Next the lines 15, 15a, 16, 17 and 18 are folded upwardly and inwardly until said line 16 coincides with line 14, whereupon the overlapping portions B, (see Fig. 3) may be pasted together to maintain the parts in the erect position shown. One end of the bag is now formed.

The formation of the other end of the bag is similar to that just described in that lines 19, 19a, 20 and 21a are folded upwardly and inwardly, line 20 coinciding with line 21a, and finally lines 22, 22a, 23 and 24 and similarly folded, said line 23 coinciding with line 21a and with the overlapping portions pasted, the bag is substantially completed. It will be noted the foldings just described, have produced flaps C and D which are now folded upwardly against the sides of the bag, and pasted thereto to complete the structure.

From the foregoing it is apparent that the formed bag is provided with an oblong bottom portion and the latter is devoid of seams of any sort. In view of this solid bottom, said bag may be snugly engaged within a garbage can, or the like, for the reception of waste material.

As previously pointed out, it is desired to provide means whereby the bag as a whole may be collapsed to assume a compact ar-

angement whereby packing and shipment is facilitated. To this end diagonal fold lines 26 and 30, and diagonal lines 27 and 31 are provided, the first pair of lines cooperating with said lines 10 and 15 to form a square, while lines 27 and 31 cooperate with lines 19 and 22 to form a square, the intersections of said pairs of diagonal lines being connected by line 25. In addition to the foregoing, 10 said blank is provided with a series of transverse lines which are designated generally by the numerals 29—33, 34—35, and 28—32.

When collapsing the formed bag, the line 25 is pressed inwardly, the bottom thus folding on the lines 26—30 and 27—31, whereupon the sides or end portions fold inwardly on the lines 32 and 33, the bag assuming the condition shown in Fig. 5. The partially collapsed bag, that is, the parts positioned opposite the line 35 are now folded inwardly, the lines 35 and 34 coinciding to produce the collapsed bag shown in Fig. 6. In this condition the bags are ready for shipment and when a bag is to be used the same may be 25 conveniently unfolded to the position indicated in Fig. 4.

While the present is a disclosure of the preferred embodiment of the invention, it is to be understood that the invention is not 30 limited thereto, as various changes in the minor details of construction, proportion and arrangement of parts may be resorted to without departing from the spirit of the invention as defined in the appended claims.

35 I claim:

1. A paper bag having a rectangular bottom whose length is greater than its width and having diagonal fold lines extending angularly from its corners and a fold line connecting the intersections of said diagonal fold lines, the arrangement of fold lines permitting collapsing of said bottom between the sides of the bag when the ends of the latter are folded in juxtaposition.
- 40 2. A paper bag having a rectangular bottom whose length is greater than its width and having diagonal fold lines extending angularly from its corners and a fold line connecting the intersections of said diagonal fold lines, the distance between said intersections being less than the length of said bottom, the arrangement of fold lines permitting collapsing of said bottom between the sides of the bag when the ends of said bag are folded 45 in juxtaposition, there being fold lines arranged medially of the bag to permit folding of the sides of the collapsed bag to position the juxtaposed ends in superposed relation.
- 50 3. A blank of paper for forming a bag having a pair of parallel longitudinal fold lines extending throughout its length and a pair of transverse fold lines intersecting said pair of longitudinal fold lines and a series of diagonal fold lines constituting two angularly 55 60 65 70 75 80 85 90 95 100 105 110 115 120 125 130

enclosed areas having opposed corners in coincidence with the intersections of said longitudinal and transverse fold lines and having their inner corners spaced apart and a fold line connecting said spaced apart corners.

New York, N. Y., May 20th, 1930.
ISABELLE B. BLAKE.
